(57) CLAIM

The ornamental design for a shoe, as shown and described.

DESCRIPTION

FIG. 1 is a side view of a shoe showing my new design; FIG. 2 is a front-top perspective view thereof; FIG. 3 is a front view thereof; FIG. 4 is an opposite side front-top perspective view thereof; and, FIG. 5 is an opposite side view thereof. The even-length broken lines represent stitching that forms no part of the claimed design. The broken lines immediately adjacent to the shaded area define the bounds of the claimed design and form no part thereof. The broken lines depicting the remainder of the shoe form no part of the claimed design.
